UNITED STATES PATENT OFFICE

108,514

DESIGN FOR A COMBINATION CORSET AND BRASSIÈRE

Mario Laguzzi, Aurora, Ill., assignor to International Corset Company, Aurora, Ill., a corporation of Illinois

Application December 31, 1937, Serial No. 74,026

Term of patent 7 years

To all whom it may concern:

Be it known that I, Mario Laguzzi, a citizen of the United States, residing at Aurora, in the county of Kane and State of Illinois, have invented a new, original, and ornamental Design for a Combination Corset and Brassière, of which the following is a specification, reference being had to the accompanying drawing forming part thereof.

In the drawing:

Fig. 1 is a front elevation of a combination corset and brassière showing my new design.

Fig. 2 is a rear elevation of the same.

I claim:

The ornamental design for a combination corset and brassière, as shown.

MARIO LAGUZZI.
